UNITED STATES PATENT OFFICE

2,663,363

AUTOMATIC REFUELING BOILER DEVICE

Willy F. Krautter, Lynbrook, N. Y., Wunibald I. E. Kamm, Dayton, Ohio, and Kurt Staiger, Indianapolis, Ind.; said Krautter assignor to the United States of America as represented by the Secretary of the Air Force

Application February 13, 1952, Serial No. 271,414

5 Claims. (Cl. 158—31)

(Granted under Title 35, U. S. Code (1952),
sec. 266)

1

The invention described herein may be manufactured and used by or for the Government for governmental purposes without payment to me of any royalty thereon.

This invention relates to the automatic control of pulse jet heaters, and of the type set forth in our copending applications S. N. 144,566, filed February 16, 1950, and S. N. 129,861, now Patent No. 2,643,107, issued June 23, 1953, and in particular to the automatic operation of a fuel vaporizing boiler therefor.

An object of this invention is to provide a boiler capable of supplying a desired vapor pressure charge to a pulse jet heater.

Another object of this invention is to provide an automatic means of refilling a boiler from a reservoir when the fuel in said boiler is suddenly expended to start the pulse jet heater.

In our copending applications S. N. 144,566 and S. N. 129,861 a starter device is used to heat a spot on a pulse jet heater as well as feed fuel to the combustion chamber for starting the pulse jet heater. The starter device comprises a combustion chamber and flue portion for forming a hot spot on the pulse jet heater, and a boiler for feeding vaporized fuel under pressure to an aspirator which in turn produces a charge under pressure of fuel and air for entrance through a valve, which opens when a predetermined pressure is reached, whereupon said fuel will enter into the combustion chamber of the pulse jet heater. When this charge comes in contact with the hot spot, combustion of the charge takes place which starts the operation of the pulse jet heater, whereupon the valve shuts off the feeding of fuel from the aspirator and boiler. In order to refill the boiler in preparation for subsequent operation of the starter, fuel must be inserted by hand. The subject invention eliminates the necessity of recharging the boiler by hand and substitutes an automatic pumping means therefor.

It is therefore an object of this invention to provide an automatic means for recharging the starting device in preparation for subsequent starting of the starter device and pulse jet heater.

A still further object of this invention is to provide a pump between the reservoir and boiler which will automatically respond to the vapor pressure fluctuation in said boiler and accordingly feed fuel to the boiler when the fuel is suddenly expended and the pressure drops below a predetermined amount.

Another further object of this invention is to provide a pump comprising an expansible motor chamber and an expansible pump chamber con-

2

nected to a single pressure responsive surface, the motor chamber communicating with a boiler so as to contain the same vapor pressure as the boiler, the pump chamber communicating with a supply reservoir and boiler through inlet and outlet check valves respectively, so that upon a drop in vapor pressure in the boiler due to the fuel being charged into the pulse jet heater, the pressure in said motor chamber will correspondingly drop and operate said pressure responsive surface to compress said pump chamber and force a charge of fluid into said boiler for subsequent starting of the starter device and pulse jet heater, and upon subsequent starting, the vapor pressure in the boiler will increase so that the pressure responsive surface in the pump will be operated to extend the pump chamber and decrease the pressure therein less than the pressure in the reservoir whereupon fluid will enter the expansible pump chamber from the fuel supply reservoir.

These and other objects will become more apparent from the accompanying specification and drawings wherein similar parts have like numbers and where:

Figure 1 shows the preferred embodiment of the invention of a burner and a boiler with a vapor pressure area and combustion chamber therein connected to a pump which in turn is connected to a reservoir;

Figure 2 shows another type of pump which may be used in place of the pump in Figure 1.

Referring to Figure 1, fuel boiler 2 has a vapor pressure chamber 4 therein surrounding a combustion chamber 6 having a flue portion 15. The boiler 2 contains an outlet 3 through which fuel from the boiler may enter into a pulse jet heater (not shown) when the pressure in said boiler reaches a predetermined value. A wick 5 for starting the boiler is located in the boiler 2. The lower portion of the boiler 2 is provided with longitudinal slots 7 for entrance of air into the combustion chamber 6, and a valve operated fuel burner nozzle 8 for permitting regulatory fluid flow into the combustion chamber 6 to mix with the air therein. The fuel burner nozzle is provided with a biased metering pin 9 for regulating the fluid flow through the nozzle opening, the metering pin being held in position by a bearing having longitudinal slots 10 therein, the slots providing a means for the pressure in the vapor pressure chamber 4 to act upon a pressure responsive surface 11 and to act within the bellows 14. The pressure responsive surface 11 may be controlled by the adjusting screw 12 together with

the spring 13. The conduit 16 mounted in said boiler surrounds the combustion chamber 6 and extends through said combustion chamber at 18 into the opening 19 in the fuel burner. A pump 20 is connected to the boiler 2 by a coupling 22. Said pump 20 comprises a housing 24 having a head 25 thereon, said head having an inlet port 26 and outlet port 28 therein. Said inlet and outlet ports contain ball check valves 30 and 32. In the bottom of said housing 24 there is mounted a spring 34 carrying a single pressure responsive surface 36 thereon. A bellows 38 is openly connected to the head 25 of said housing and connected at the bottom to said single pressure responsive surface 36 thereby forming a pumping chamber 40. Another bellows 42 is openly connected at one end between the housing 24 and head 25, and is connected at its bottom portion to the said single pressure responsive surface 36 thereby forming a motor chamber 44. An orifice 47 in the head 25 of said housing 24 connects the motor chamber 44 to the boiler 2 through coupling 22. The pump chamber 40 is connected to the reservoir 46 through coupling 45.

In operation, to start the device a wick soaked with fuel in the bottom of the combustion chamber 6 is ignited through the openings 7 by a match or the like. The heat generated tends to vaporize the fuel in the boiler chamber 4 increasing the pressure therein. This pressure acts through the tube 16 on the needle valve metering pin 9, within the expansible chamber 14 on a pressure responsive surface 11 tending to open the nozzle 8 to the combustion chamber 6 thereby feeding fuel thereto. The heat generated in the flue portion 15 of combustion chamber 6 forms a hot spot on the pulse jet heater. When the pressure in the boiler reaches a predetermined amount sufficient to open a valve to the aspirator (not shown) a charge of fuel vapor in the boiler 2 escapes through the outlet 3 into the aspirator thence into the combustion chamber of the pulse jet heater. When the charge contacts the hot spot it will immediately ignite and start the pulse jet heater shutting off the valves to the starter device. The pressure in the boiler 2 having dropped a considerable amount due to the vaporized fuel being expended to the pulse jet heater, the opening in nozzle 8 will be closed by the metering pin 9 being forced into closed position by the spring 13 and pressure responsive surface 11 thereby extinguishing the fire in the combustion chamber 6 for lack of fuel. The pressure in the boiler chamber 4 will be accompanied by a drop in pressure in the expansible motor chamber 44 because of the orifice 47. The spring 34 will overcome the pressure in motor chamber 44 and move the pressure responsive surface upwardly compressing the expansible pumping 40 and forcing fuel through the check valve 30 into the boiler 4 for the next time to start the pulse jet heater. When the burner is started again at a subsequent time and the fuel in boiler chamber 4 begins to vaporize, the pressure will increase in the boiler chamber 4 as well as in the expansible motor chamber 44 which will cause the chambers 44 and 40 to expand whereupon the pressure in the pump chamber 40 will decrease to an extent to permit the ball check valve 32 to open and allow fluid to flow into the pump chamber 40 from the reservoir or fuel tank 46.

Referring to Figure 2 which discloses another modification of the pump shown in Figure 1 wherein a push rod 50 extends through the head

25 of said housing 24 down adjacent to the piston 36. A button 52 is mounted on top of the push rod 50 which is sealed against outside elements by bellows 54. The plug 56 is mounted in the top portion of the housing 24. By repeatedly pushing and releasing the button 52 and push rod 50, the piston 36 will move back and forth so that the pump chamber will deliver fuel to the boiler as long as spring 34 is able to overcome the pressure on ball check valve 30 and on piston 36. Instead of being located at the top of the housing 24 the push rod may be arranged in the bottom of the housing of the pump. In this case sealing the passage opening around the push rod and housing is not necessary.

It is apparent the specific embodiments shown above have been given by way of illustration and not by way of limitation and that the structures above described are subject to wide variation and modification without departing from the scope or intent of the invention, all of which variations and modifications are to be considered as equivalents and be included within the scope of the present invention.

Whereby I claim:

1. An intermittent burner device of the character described comprising a fuel boiler, a combustion chamber having a flue portion extending through said boiler in heat exchange relation therewith, a burner in said combustion chamber, valve means for controlling fuel flow through said burner, a conduit connecting the vapor space in said boiler with said burner valve means, means responsive to fuel vapor pressure in said boiler and connected to said valve means to open and close said valve means, a source of fuel supply, a pump comprising an expansible pump chamber having inlet and outlet valves and connected to said fuel source and to said boiler respectively, an expansible motor chamber operatively connected to said pump chamber, said motor chamber being connected to said boiler and actuated in response to an increase of pressure therein to actuate said pump to draw in a charge of fuel from said fuel supply, and said motor chamber including means for actuating said pump to discharge fuel through the outlet valve upon a drop in pressure in said boiler below a predetermined value, whereby the means responsive to boiler vapor pressure and connected to said burner valve means actuates said burner valve to cut off fuel supply to said burner and said pump recharges said boiler with fuel preparatory for a subsequent need for operation of the burner device.

2. An intermittent starter device, comprising a combustion chamber and flue mounted within a boiler, said boiler having inlet and outlet ports, a fuel burner nozzle for injecting fuel into the combustion chamber, a conduit connecting said boiler and said fuel nozzle for transmitting vapor fuel under pressure to said fuel nozzle from said boiler, said fuel nozzle is provided with a biased metering pin which acts as a needle valve and is mounted within an expansible chamber, said expansible chamber having a pressure responsive end surface for actuating said metering pin, said expansible chamber being extended by the vapor pressure therein, a spring for collapsing said expansible chamber when the vapor fuel under pressure in the boiler and expansible chamber is expended, said boiler is provided with a fuel supplying device for automatically replenishing the expended vapor fuel, said fuel supply device comprises a housing having an ex-

expansible motor chamber connected to the boiler through an open passageway so that the motor chamber and boiler are under the same vapor pressure, an expansible pump chamber connected to the boiler and a fuel supply reservoir by passageways containing check valves therein, said expansible chambers being closed at one end by a common movable pressure responsive surface and openly connected to said passageways and housing at the other end, and a spring means biasing said common movable pressure responsive surface in the lower portion of said housing adapted to move said common surface in an upwardly direction, so that upon the vapor fuel under pressure in said boiler being suddenly expended the drop in pressure will permit the metering pin to close the fuel burner jet, and said expansible motor chamber will be compressed by said spring means and force the fuel from said expansible pump chamber into said boiler for subsequent operation of the starter device, and upon subsequent starting the expansible pump chamber will extend and refill with fuel from said reservoir.

3. For use with a pulse jet heater, in combination, a fuel vaporizing boiler for supplying vaporized fuel to the pulse jet heater, a pump responsive to pressure fluctuations in said boiler for automatically recharging said boiler with fuel and communicatively connected thereto by an open passageway, a supply reservoir communicatively connected to said pump for supplying fluid thereto, said pump comprising flexible bellows forming an expansible pump chamber located within another flexible bellows forming an expansible motor chamber, both of said bellows being closed at one end by a single pressure responsive surface which is biased by a resilient means, an outlet check valve in said open passageway for regulating fluid flow between said pump chamber and boiler, an orifice between said open passageway and motor chamber so that the boiler and motor chamber will be subject to the same pressure at all time, an intake check valve in said connection with said reservoir to permit intermittent fluid flow into said pump so that when the fuel in said boiler is suddenly used up, a drop in pressure in said boiler will be accompanied by a drop in pressure in said motor chamber permitting said resilient means to compress said motor chamber and force fluid out of said pump chamber through said outlet check valve and open passageway into said boiler to recharge said boiler for subsequent operation, where, upon subsequent operation,

said fuel will vaporize and increase the pressure in said boiler and motor chamber and force said pressure responsive surface against said spring, resulting in a decrease of pressure in said pump chamber less than in said reservoir, thereby opening said inlet check valve for fluid flow into said pump chamber.

4. In combination, a pressurized fuel boiler intermittently connected to a fuel reservoir by a pump device for feeding fuel to said boiler from said reservoir, said pump device comprising pressure orifice means communicating with said boiler, and spring means opposing a pressure responsive surface to operate said pump, said orifice means permitting the force of said spring means to overcome the force exerted by the pressure in said pump device on said pressure responsive surface when the pressure in said boiler drops below a predetermined amount after the fuel is suddenly expended, thereby fluid will be forced from said pump device into said boiler for recharging said boiler for subsequent operation, said pressure orifice means and said spring means cooperating with said pressure responsive surface to provide means for permitting fuel to flow into said pump device from said reservoir when the force due to the pressure in said pump from said boiler overcomes the force exerted by said spring.
5. The combination of claim 1 wherein the valve means for controlling fuel flow through said burner comprises a metering pin, a pressure responsive surface in engagement with said metering pin for controlling the movement thereof, said surface being subject to the vapor pressure from said boiler to open said burner, spring means in opposition to said surface adapted to close said burner when the vapor pressure from said boiler drops below a predetermined value.
